Application February 7, 1940, Serial No. 317,686

5 Claims. (Cl. 40—130)

This invention relates to a device for display or advertising purposes and relates more particularly to illuminated characters in combination with a clock dial.

Illuminated clocks have always been popular when provided for general use as when located in public places such as waiting rooms, stores, street corners or the like. Since the introduction of the electric clock the popularity has grown and such clocks have been employed to serve both as a time-piece for the public and to carry advertising matter as compensation for the installation and maintenance of the clock.

The disposition and arrangement of the advertising legends present a problem since in many instances the clock must be of a pleasing and ornamental character to the end that any unsightly advertising legends, such as company names or description of products, tends to detract from the attempt to provide an ornamental or artistic effect. On the other hand any advertising matter disposed remote from the actual dial to which the attention of the public is directed, loses its value for the purpose intended.

It is an object of the present invention, therefore, to provide a clock for public use in which a legend may be disposed in direct line with the time dial and at the same time give a novel pleasing effect.

Another object of the invention is to provide a clock dial cover with light diffusing characters.

Another object of the invention is to provide light diffusing characters on a cover plate and having a surrounding field harmonizing with the surface or background of the dial.

Although the present invention may find other uses it is particularly adapted for application to a clock, such for example, as that shown in Patent No. 1,994,950 issued March 19, 1935. In this patent a clock is shown with light absorbing dial surface, as for example, surfaced with black paint. The hour numerals are light reflecting or white, as are also the hour and minute hands.

This clock has a casing so constructed as to provide a space between the dial and the cover plate or glass. In this space is provided a discharge lamp, preferably shaped to the contour of the casing so that light rays are directed to illuminate the numerals and the hands.

It was found that by utilizing the cover glass, an extremely novel effect could be produced while providing a conspicuous location for a legend.

The name or mark of the advertisement is cut

into the cover glass in such manner as to provide characters of light diffusing surfaces. These surfaces interrupt and diffuse the light rays emanating from the light source. This of itself produces an ornamental effect, but is added to by taking advantage of the black face of the dial. This is accomplished by providing a local field of black opaque paint surrounding the diffusing characters. This field need only extend over a relatively small area and when viewed from a distance, harmonizes with the black face of the dial. The result is to make the diffusing characters stand out as though suspended without support in front of the clock giving not only a novel effect, but permitting the disposition of an advertising legend in the line of sight of anyone using the clock, not only without annoyance, but creating a certain degree of speculation and interest, which adds to the value of the invention from the standpoint of its usefulness.

The invention will be more clearly understood from the following description together with the accompanying drawing in which,

Fig. 1 is a front view of a clock having characters supported and arranged in accordance with the invention.

Fig. 2 is an enlarged side view of the clock with a portion of the casing and cover glass removed and

Fig. 3 is an enlarged fragmentary view of the clock, the cover glass being shown in cross-section on a plane longitudinally of the light diffusing characters and their local field.

The selected embodiment of the invention may comprise a clock casing 18 having a compartment or body 11 and a compartment 12. The compartment 12 consists of a dial 13, portion 14 of the casing and a cover glass or plate 15. The clock structure may either be mechanical or electrical and need not be further described. The dial 13 is faced with a light absorbing coating, as for example, black paint 16 on which are disposed the usual numerals of light reflecting material. The hands 17 and 18 are also provided with light reflecting surfaces.

A light source in the form of a discharge lamp 19 is disposed in the lower portion of the compartment 12 in such manner that the portion 14 of the casing prevents direct radiation from passing through the cover glass. The numerals, however, are illuminated by direct radiation as are the hands and since the dial face is black a sharp contrast is effected giving visibility to

the hands and numerals for relatively great distances.

In accordance with the present invention the cover glass is provided with light reflection or light diffusing portions in the form of characters 20, such as a name or legend. Surrounding these characters is provided a local field 21 of light absorbing material, as for example, black paint similar to the dial surface so that from a distance the two surfaces merge or harmonize. The local field loses its visible identity when viewed against the black dial background. The light diffusing characters on the cover glass, however, pick up the light rays from the source and become distinct and exceedingly brilliant. Furthermore, when viewed from a distance the characters appear to be suspended without support in front of the clock. This is due to the optical effect of the dark field and the transparency of the cover glass.

Good results have been obtained by grinding or etching the surface of the glass to form letters, numerals or designs, but it is possible to provide suitable light diffusing portions by using thin layers of light diffusing material, such as nitrocellulose products, or etched sheet glass.

Novel effects may be provided by coloring the characters as by tinting without destroying the necessary transparency.

Although one embodiment of the invention is shown and described herein it is to be understood that variations and modifications may be made therein without departing from the scope of the appended claims.

What is claimed is:

1. In combination with a clock, a dial having a dark face, a transparent cover plate spaced from said dial, translucent light diffusing characters on said plate, a local opaque field sur-

rounding said characters blending with said dark surface and a light source disposed between said dial and plate.

2. In combination with a clock, a dial having a dark surface, a transparent cover plate spaced from said dial, light diffusing characters on said plate, a local opaque field surrounding said characters and blending with said dark dial surface and a light source for illuminating said characters.

3. In combination with a clock having a casing and a dial face having a dark surface, a transparent cover plate spaced from said face, light diffusing portions on said cover plate and a local field surrounding said portions, said field being in harmony with said dark surface, and means for illuminating said portions causing them to contrast with the surrounding field and said dark surface.

4. In combination with a clock having a casing, a transparent cover plate, supported by said casing, a dial in said casing spaced from said plate, a source of illumination within said casing and between said plate and dial, said dial having a light absorbing surface and light reflecting characters, light diffusing characters on said plate and a local light absorbing field surrounding said last mentioned characters.

5. In combination with a clock having a light absorbing dial surface and light reflecting characters, a source of illumination for said characters, a light transmitting cover plate for said clock, said plate having portions roughened for the diffusion of light rays, and a local opaque field surrounding said portions and blending with said dial surface to accentuate the diffused light passing through said portions.
